Gerald L. Sittser, 249 Fuller SE., Grand Rapids, Mich.

Filed Apr. 21, 1960, Ser. No. 60,268

Term of patent 14 years

(Cl. D42—7)

FIG. 1

FIG. 2

FIG. 3

Fig. 1 is an elevational view of a clock showing my new design.

Fig. 2 is an end view thereof.

Fig. 3 is a sectional view thereof, taken on line III—III of Fig. 1.

The time zones are distinguished from one another by different colors or shades.

The essential features of my design reside in the portions shown in full lines.

I claim:

The ornamental design for a clock, substantially as shown and described.
